(57) **CLAIM**

The ornamental design for a non-opaque light cover for a light fixture, as shown and described.

DESCRIPTION

FIG. 1 is a perspective of a non-opaque light cover, a base of the light cover for use in securing the light cover to a light fixture body being shown in broken lines;
 FIG. 2 is a front elevational view of the light cover, the back, left, and right elevational views being identical to the front elevational view;
 FIG. 3 is a top plan view of the light cover; and,
 FIG. 4 is a bottom plan view of the light cover.
 The broken lines in the drawings indicate environmental structures which form no part of the claimed design.
